UNITED STATES PATENT OFFICE.

SARAH S. STILWELL WEBER, OF PHILADELPHIA, PENNSYLVANIA, ASSIGNOR TO
W. H. & A. E. MARGERISON & CO., OF PHILADELPHIA, PENNSYLVANIA, A FIRM
COMPOSED OF WILLIAM H. MARGERISON AND ALBERT MARGERISON.

DESIGN FOR A TOWEL.

Application filed October 27, 1927. Serial No. 23,908. Term of patent 8½ years.

To all whom it may concern:

Be it known that I, SARAH S. STILWELL WEBER, a citizen of the United States, residing at Philadelphia, in the county of Philadelphia and State of Pennsylvania, have invented a new, original, and ornamental Design for Towel, of which the following is a specification, reference being had to the accompanying drawing, forming part thereof.

The figure is a perspective view of a towel showing my new design.

I claim:

The ornamental design for a towel, as shown.

SARAH S. STILWELL WEBER.
